UNITED STATES PATENT OFFICE

KENNETH J. UNWIN, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

BOBBIN SUPPORT FOR WEFT-REPLENISHING LOOMS

Application filed November 22, 1928. Serial No. 321,240.

This invention relates to improvements in yieldable bobbin supports for weft replenishing looms and it is the general object of the invention to provide a simple support which will be yieldable in the direction in which the lay advances and at the same time present a substantially smooth surface for the passage of the weft end extending from the bobbin to the thread holder.

10 In weft replenishing looms the bobbins are stored in a plurality of vertical reserve stacks and immediately prior to transfer a bobbin will be called from one or another of the stacks to be delivered to yielding supports. The latter are usually inclined so that the bobbins from the several stacks may roll to a common transfer position. There is always a short end of filling extending from the bobbin to the thread holder and this end slides over the bobbin support so that the portion of the support which is in engagement with the bobbin should be uninterrupted or smooth enough not to interfere with the downward movement of the weft end.

20 In co-pending application Ser. No. 251,992 filed by King there is set forth a bobbin holder or support made of a coil spring all the coils of which are close together so as to present the smooth surface already mentioned. In that application, however, the coils are closely adjacent each other throughout the entire length of the support and the result is that should a bobbin be misplaced during the forward movement of the lay so as to engage the support the latter will receive a force which is more or less in line with its axis. Under these conditions, due to the fact that the coils are close together the support cannot yield and there results either breakage to the bobbin or a change in the setting of the support.

30 It is an important object of my present invention to provide a bobbin support formed of a single piece of wire coiled on itself, some of the coils being close together and some spaced, the coils which are close together being adapted for engagement with the bobbin as the latter moves toward transfer position, while the spaced or separated

coils are located outside the range of movements of the bobbins so as not to be able to interfere with the weft end but to be capable of yielding under the previously described conditions to prevent breakage of the bobbin or misadjustment of the support. 55

40 It is a more specific object of my present invention to provide a support as an article of manufacture which shall have closed coils on its bobbin supporting end and preferably though not necessarily closed coils at the end where it is supported, together with open coils between the sections of closed coils, the open coils acting to permit yielding of the bobbin supporting tip of the support toward the holder for the support in a direction substantially coincident with the axis of the support. 60 65

50 With these and other objects in view which will appear as the description proceeds, my invention resides in the combination and arrangement of parts hereinafter described and set forth in the claims. 70

55 In the accompanying drawings wherein a convenient embodiment of my invention is set forth,

Fig. 1 is a central section through a magazine having my invention applied thereto, looking toward the tip ends of the bobbins, 75

60 Fig. 2 is a horizontal section on line 2—2 of Fig. 1, 80

65 Fig. 3 is a diagonal front elevation taken in the direction of arrow 3, Fig. 1,

70 Fig. 4 is an enlarged section on line 4—4 of Fig. 2, and 85

75 Fig. 5 is a detailed view similar to a portion of Fig. 1 showing the manner in which a misplaced bobbin may engage the support.

80 Referring particularly to Figs. 1 and 2, I have shown a magazine frame having an outer plate M having vertical guides 10 which may receive the tips of the bobbins. B. Inner plate 13 may have corresponding guides 9 for the butts of the bobbins, 95 each pair of guides 9 and 10 forming a guideway or bobbin compartment. Located at the bottom of each of the guideways is a cradle 11 which may be rocked at appropriate times to deliver the lowermost bobbin 100

of the vertical stack corresponding to the active shuttle.

The magazine includes in its construction tie rods 12 which extend between the inner plate 13 and outer plate M, shown in Fig. 5. The inner plate is supported by means not shown and it is through the tie rods that the outer plate is supported.

The loom may be provided with the lay 10 L carrying a shuttle S which as shown in Fig. 1 may carry a depleted bobbin D. The lay L will always assume substantially the same position with respect to the magazine when in its foremost position and the shuttle will be placed to receive a bobbin located 15 in the transfer position indicated at T in Fig. 1. The matter thus far described forms no part of my present invention and may be substantially the same as shown in prior 20 patent to Ryon No. 1,030,748.

My present invention relates more particularly to the form of yielding bobbin support which holds a bobbin in transfer position and in carrying my invention into effect 25 I provide the lower tie rods each with a holder 20. Each of said holders is provided with an inclined bore 21 and these bores are so disposed that the bore in the forward holder will extend downwardly and rearwardly while the bore in the rear holder will 30 extend downwardly and forwardly. As shown herein the bores 21 are located farther from the center of the magazine than are the corresponding tie rods 12, but in other respects the holder may perform the same 35 function as the corresponding parts shown in the aforesaid King application. As the supports for both the front and back holders are the same I will describe but one.

Referring particularly to Fig. 5 it will be 40 seen that I have provided a support 30 having a lower conical end 31 which extends from an upwardly inclined substantially cylindrical portion 32. The coils forming the 45 conical and cylindrical portions 31 and 32, respectively, are closely wound as clearly shown in Fig. 5. The upper end of the support 30 is formed of closely wound coils as 50 shown at 33, said coils being wound as set forth in Fig. 5 to provide a more substantial holding surface to engage the bore 21. A screw 34 may extend through the holder and clamp the cylindrical closely wound portion 33 to hold the support tightly in position.

That portion of the support which lies between the cylindrical portions 32 and 33 and indicated herein at 35 is made up of a plurality of spaced coils which are wound from the same wire which forms the closely wound 55 portion of the support. The length of the cylindrical and conical lower support will be determined by the location of the outer 60 stacks of bobbins. As shown in Fig. 1 the cylindrical portion 32 will extend from the 65 central portion of the magazine to a point

substantially below the corresponding outer stack of bobbins, whether the support be in front of or behind the center of the magazine. With this arrangement the weft ends W which extend from the bobbins will always engage closely wound coils and will therefore not be entangled with the latter and will be free to move downwardly toward transfer position with the bobbin drawn from either of the outer stacks. This relation also exists with bobbins drawn from either of the inner stacks. The bores 21 are so disposed with respect to the tie rods that there is considerable length of the support wound with the open coils as clearly shown 80 in Fig. 1.

As previously stated it occasionally happens that a bobbin will be misplaced on a forward beat of the lay and will tend to impart an endwise thrust to the forward support tending to move the latter toward its holder. Under these conditions the bobbin may assume the position shown at 40 in Fig. 5 with its butt in engagement with the conical portion 31 and with the lay moving in the 90 direction of arrow 41. As the lay continues its forward movement the open coils 35 will be compressed so that the length of the support may be shortened along its axis with the conical tip moving toward the corresponding 95 holder. After the bobbin has been taken from its improper position the holder because of its inherent resilience will be restored to normal position.

From the foregoing it will be seen that I 100 have provided a very simple form of yielding bobbin support wherein the bobbin supporting portions may move in any direction from their normal position, to be returned to normal position after deflection by the inherent 105 resilience of the support. More specifically it will be seen that I have provided a yielding bobbin support formed of a single piece of wire having bobbin supporting and holder engaging portions of closely wound coils and an intermediate portion of open wound coils to permit longitudinal movement of the bobbin supporting part thereof toward the holder part. It will be seen by reference to Fig. 1 110 that the open coils are located in such a position that they will not interfere with the weft ends W but will always be out of the range of movements of the bobbins as the latter move from the several reserve stacks in the 115 magazine toward transfer position.

Having thus described my invention it will be seen that changes and modifications may be made therein by those skilled in the art without departing from the spirit and scope of the invention and I do not wish to be limited to the details herein disclosed, but what I claim is:

1. In a weft replenishing loom, means defining a guideway along which a plurality of bobbins may move toward transfer posi- 130

tion, a bobbin support formed of a piece of wire coiled on itself, said support having some of the coils closely adjacent each other and having other coils open or separated with respect to each other, the open coils being located on that portion of the support which lies to that side of the guideway for the bobbins which is opposite the position occupied by a bobbin when in transfer position.

10 2. In a weft replenishing loom means defining a guideway along which bobbins move toward transfer position, a bobbin support formed of a piece of wire coiled on itself and diagonally disposed with respect to the guideway for the bobbins and extending on opposite sides of the latter, the coils on one side of the guideway being closely wound to present a substantially smooth surface for a weft end extending from a bobbin, and 15 the coils on the opposite side of the guideway being spaced to permit a yielding of the support in both directions along the line parallel to its axis.

3. In a weft replenishing loom, means defining a guideway along which bobbins may pass toward transfer position, a control device located at the bottom of the guideway to pass the bobbins one at a time from the guideway toward transfer position, and an 20 inclined flexible bobbin support formed of a single piece of wire coiled on itself around a substantially straight axis, the coils located on one side of the control device being closely adjacent each other to present a smooth surface 25 face to a weft end extending from a bobbin passing toward transfer position, and the coils on the opposite side of the control device being spaced apart to provide a part of the support which is capable of yielding in opposite directions along the line substantially parallel to the axis of the support.

4. In a weft replenishing loom, means defining a substantially vertical guideway along which bobbins may pass toward transfer position, a flexible bobbin support extending diagonally and having portions thereof disposed on both sides of the guideway, said support being formed of a single piece of wire coiled on itself, a holder fixed 45 with respect to the loom and affording supporting means for the support, the coils of the support which are located on one side of the guideway being closely adjacent each other to define a substantially smooth surface 50 along which a weft end may extend from a bobbin moving toward transfer position, and the coils of the support lying on the opposite side of the guideway being spaced apart to present a portion of said support which may 55 be compressed along a line substantially parallel to the axis of said support and toward the holder.

5. In a weft replenishing mechanism, a plurality of guideways along which bobbins 60 may move toward transfer position, control

means at the bottom of each guideway to deliver a bobbin toward a common position between the guideways from which the bobbin may be transferred, and a flexible bobbin support for one of the guideways extending on opposite sides of the latter so that one portion projects toward the position from which a bobbin is transferred and the other portion extends away from such position, said support being formed of a single piece of wire coiled on itself, the coils which lie between the guideway and the position from which the bobbin is transferred being closely adjacent each other to present a substantially uninterrupted surface along which a weft end from the bobbin may extend, and the coils of that portion of the support which lies on the other side of the guideway being spaced from each other and being compressible under the action of the force moving from the transfer position of a bobbin toward the open coils.

6. In a weft replenishing loom, means to hold a bobbin in transfer position, said means including a bobbin support formed of a piece of wire coiled on itself, said support being yieldable in all directions from its normal bobbin supporting position, being capable of flexing in any angular direction from the normal position and being capable also of moving in opposite directions along a line substantially parallel to the axis thereof.

7. In a weft replenishing loom, means to support a bobbin in transfer position, said means including a coil spring support formed of a piece of wire coiled on itself around a substantially straight axis and having a bobbin supporting portion, the bobbin supporting portion being movable in any angular direction from the normal axis of the support and being movable along the axis in opposite directions when said coil spring is in its normal condition due to the inherent resilience of a portion of the support caused by adjacent coils of the latter being spaced from each other.

8. In a weft replenishing loom, means to support a bobbin in transfer position, a holder, said means including a coil spring one end of which is held securely in the holder and the other end of which has a bobbin supporting tip, said support being of substantially cylindrical form and having a normally straight axis, the supporting tip being movable in any angular direction with respect to the normal axis of the support, and being movable also along the axis toward the holder while said one end is held securely to the holder.

9. In a weft replenishing loom, means to guide a bobbin along a path from reserve position to transfer position, and a bobbin support having a portion extending into the path of the bobbin and having another portion lying outside the path of the bobbin, said support including a piece of wire coiled

on itself, the portion of the support lying in the path of the bobbin being formed of coils would closely together, and the portion of the support lying behind the path having separated coils which are readily compressible under a force acting on the closed coil portion.

10. A bobbin support for weft replenishing looms comprising a single piece of wire coiled on itself around an axis, said support having portions which are noncompressible to engage the bobbin and the weft extending therefrom, and said support having other portions which are compressible in a direction along the axis of the support.

11. A coil spring bobbin support for a weft replenishing loom to hold a bobbin in transfer position, said support comprising a piece of coiled wire to engage the bobbin and made so that it may be stretched along its entire length but is compressible throughout a portion only of its length.

12. A bobbin support to hold a bobbin in transfer position formed of a coiled wire and having noncompressible portions to engage a bobbin and having also compressible portions integral with the noncompressible portions, whereby the over all length of the support may be decreased under a compressing force 30 without permanently deforming the support.

13. A bobbin support to hold a bobbin in transfer position, said support including a single piece of wire coiled on itself and having certain coils closely adjacent each other 35 to present a substantially uninterrupted surface along which a thread may extend and having another portion formed of open coils which are compressible.

14. A bobbin support to hold a bobbin in transfer position for weft replenishing loom, said support including a piece of wire coiled on itself and having at its opposite ends closely wound coils and having open coils intermediate the closely wound coils.

45 15. A bobbin support to hold a bobbin in transfer position, said support including a single piece of wire wound on itself, the coils at one end being closely adjacent each other to present an uninterrupted and substantially smooth surface for a weft thread, said support having a holding portion by which the support may be held in position, and spaced coils formed between the closely wound portion and the holding portion.

55 16. A bobbin support for weft replenishing mechanisms to hold a bobbin in transfer position, said support formed of integral compressible and non-compressible portions.

In testimony whereof I have hereunto affixed my signature.

KENNETH J. UNWIN.
